PLAYGROUND CLIMBER

Vello Hubel, Toronto, Ontario, Canada, assignor to Protective Plastics Limited, Don Mills, Ontario, Canada, a corporation of Canada

Filed Aug. 16, 1966, Ser. No. 3,479

Term of patent 3½ years

(Cl. D34—5)

FIG. 1 is an elevational view of a playground climber embodying my new design;

FIG. 2 is an elevational view of the device partly in section and taken generally through the line 2—2 of FIG. 3; and

FIG. 3 is a bottom plan view of the device.

I claim:

The ornamental design for a playground climber, as shown.
